ABSTRACT OF THE DISCLOSURE

A golf practising device comprising a body having a hole extending completely through it, which hole has a larger diameter at one end than the other, and two lids pivotally attached to the body on opposite sides thereof.

The body and lids may simulate the appearance of a book. The holes may be used as putting cups and the lids as ramps extending toward the holes. The body may be made by vacuum molding one sheet of material to form an apertured flanged member and securing a face forming apertured sheet to the flange portion thereof.

DISCLOSURE

This invention relates to devices for practising golf and in particular to devices suitable for practising putting.

According to British Pat. No. 1,015,958 such a device comprises an approximately rectangular body adapted to lie on the floor and having a cylindrical hole in it and a lid attached to the body, the lid being movable between two positions so that in one position it covers the upper side of the body and covers the hole and in the other position it rests on the floor at one edge to form a ramp up which a golf ball can be putted to fall into the hole.

The main object of the present invention is to provide a similar device which is both easy to manufacture in large quantities and provides additional interest to the user.

According to the present invention a golf practising device comprises a body having a hole extending completely through it, which hole has a larger diameter at one end than the other, and two lids pivotably attached to the body on opposite sides thereof.

The smaller diameter may be provided by an inwardly extending flange at that end.

Thus the user can open either lid to form a ramp up which a golf ball can be putted so as to use either the large end or the small end of the hole.

The sides of the body together with one large face thereof and the sides thereof may all be formed as an integral piece of moulded sheet material.

A constructional form of the invention will now be described by way of example with reference to the accompanying drawings, wherein:

2

FIG. 1 is a perspective view of a device made in accordance with the invention;

FIG. 2. is a similar view but showing the parts of the device in different positions, and

5 FIG. 3 is a sectional view on the line A—A on FIG. 1 but showing the parts in different positions.

The device has a substantially rectangular body 10 having a hole 11 extending completely through it centrally thereof and two rigid flat rectangular lids 13, 14 10 pivotally attached to the body on opposite sides along adjacent long edges of the body. The body could however have a square or other shape.

The body is made by vacuum moulding a sheet of material 15 to form one large face 16 of the body, the 15 wall 17 of the hole 11 an annular flange 19 projecting inwardly at one end of the wall 17 and the four sides 20. The other large surface is then covered by a flat sheet 21 having a hole corresponding to that of the flange 19, fixed to the sheet 15. The sides may be covered with 20 material to resemble leaves of a book and the inside surfaces of the lids and the two large surfaces of the body may be covered with green baize.

A back portion 23 is glued to one long side and the 25 two lids 13, 14 are fixed pivotally to this back portion.

25 The lids are suitably decorated so that the whole device looks like an ordinary book.

I claim:

1. A golf practising device comprising a body, opposed 30 first and second faces on the body, a hole extending through the body from the first to the second face and having a larger diameter at one face than the other, first and second lids respectively hinged to corresponding edges of the first and second faces of the body, each lid being movable from a closed position covering its associated 35 face to an open position in which it constitutes a ramp leading to its associated face when the device is disposed with its other closed lid on a support surface.

2. A golf practising device according to claim 1 in which the body comprises a moulded sheet forming one 40 of said faces, the wall of the hole and four side walls and a flat sheet constituting the other of said faces secured to said sheet of material.

3. A golf practising device according to claim 2 in the 45 form of a simulated book in which the body simulates the pages of the book and the lids simulate the covers.

4. A golf practising device according to claim 3 comprising a book portion joining the hinged edges of the lids.
